UNITED STATES PATENT OFFICE.

WILLIAM T. SMITH, OF PHILADELPHIA, PENNSYLVANIA.

DESIGN FOR A RUG.

SPECIFICATION forming part of Design No. 22,285, dated March 14, 1893.

Application filed July 16, 1892. Serial No. 440,283. Term of patent 7 years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Fabric, of which the following is a specification, reference being had to the accompanying drawing.

The leading features of my design are the representation of a Grand Army badge, a center scroll in form of a shield, upon which is represented thirteen stars, and a five-pointed star, that forms a pendant to the Grand Army badge. The shield is represented as hung against two crossed cavalry sabers. On the right of the shield is represented a stack of muskets, with mountains and sky in the back

ground. On the left is represented two cannons at a cross, below them a pyramid of shot or shells, and scenery in the background; the whole surrounded by a border in which is represented various emblems used by different army corps. The whole as is illustrated by the accompanying drawing, which is sufficient to enable others skilled as fancy weavers, to produce my invention.

What I claim as new, and desire to secure by Letters Patent, is—

The design for a woven fabric, as shown in the accompanying drawing.

W. T. SMITH.

Witnesses:
